ICE TRAY

Carl H. Synnestvedt, Bryn Athyn, Pa., assignor to Philco Corporation, Philadelphia, Pa., a corporation of Pennsylvania

Application November 11, 1943, Serial No. 509,888

5 Claims. (Cl. 62—108.5)

1

The present invention relates generally to domestic refrigeration and pertains more particularly to ice trays adapted for use in the fast freezing compartment of a household mechanical refrigerator.

It is one of the more important objects of the invention to provide a tray capable of forming individual ice masses, which is constructed and arranged so that the ice masses, when formed, are automatically loosened and lifted outwardly of the tray to be readily grasped and removed by hand, as and when needed.

An equally important object of the present invention resides in the provision of a tray adapted to form ice masses or cubes, which is characterized by its simplicity of construction and which can be manufactured at relatively low cost, and used in a conventional evaporator included in the refrigerating system of household mechanical refrigerators without requiring special installations therein.

It is also among the more important objects of the invention to provide a tray of the character set forth having means defining a mold to receive a quantity of water to be frozen into ice, said mold and tray cooperating to form a space therebetween, which space is filled with a solution having a freezing point lower than that of water, so that the expansion forces of such a solution may be utilized to break the bond between the mold and water ice frozen therein, the structure and association of the tray and mold being such that the whole of said expansion forces are controlled for full and direct action on the mold to insure automatic loosening and lifting of the ice from the latter.

A further object of the invention resides in the provision of an ice tray of the general type mentioned which incorporates means facilitating ready and accurate filling of the separate cups or molds to a predetermined substantially uniform level throughout the entire tray, so that raising of the frozen cubes predisposes the same in a position for ready access and removal.

Other objects and advantages of the invention will become apparent to those skilled in the art from the following description based upon the accompanying drawings, in which:

Figure 1 is a perspective view illustrating one form of the invention;

Figure 2 is an enlarged transverse section taken on line 2—2, Figure 1;

Figure 3 is a cross-sectional detail on an enlarged scale, looking in the general direction indicated by arrows 3—3, Figure 1;

2

Figure 4 is a vertical section looking in the general direction of arrows 4—4, Figure 1;

Figure 5 is a perspective illustration of a portion of the frame work included in the structure of the ice cube molding member;

Figure 6 is a somewhat diagrammatic representation of the action of the expansion forces in freeing and lifting an ice cube in that form of the invention shown in Figures 1 and 2;

Figure 7 is a top plan of a portion of an ice cube tray constructed in accordance with another form of the invention;

Figure 8 is a longitudinal section taken on line 8—8, Figure 7; and

Figure 9 is a somewhat diagrammatic representation of the action of the expansion forces in freeing and lifting an ice cube in that form of the invention illustrated in Figures 7 and 8.

Referring more particularly to the drawings, 20 wherein like characters of reference designate corresponding parts throughout, there is shown an ice cube tray 10 which may be stated to comprise two essential elements, that is, a tray member 11 and ice cube mold member 12.

25 The tray member 11 is made of rigid material, preferably metal, and is given a generally rectangular shallow configuration. The ice cube mold member 12 is preferably made of pliable material such as rubber, plastic or the like, and, as shown, may be molded in one piece and shaped to form a plurality of water receiving and retaining cups 13 of generally frusto-conical shape.

In accordance with the invention, the marginal edges of the ice cube mold member defining the 30 cups 13, are to be maintained in fixed position with respect to the tray member 11 and for that purpose, a wire frame 14 provided with cross-pieces 15 and 16 may be embedded in beads 17 at 35 said marginal edges of the mold, thereby imparting rigidity thereto. The longitudinal and side edges of the mold member 12 are preferably secured to the corresponding edges of the tray member 11 and this may conveniently be accomplished by forming the tray member with a generally L-shaped flange 18 providing a seat as shown at 19 for the bead 17 surrounding the mold member, said flange then being pressed down or rolled over said bead in the manner more clearly shown in Figure 1 of the drawings.

45 When assembled, the tray member 11 and mold member 12 cooperate to define a space 20 between adjacent walls thereof and also between the adjacent outer walls of the cups 13, said space 20 being filled with a solution having the properties 50 to be fully described hereinafter. In order to

provide means for introducing the solution within the space 20, the tray member 11 is formed with an opening 21, preferably located at the upper portion of one wall thereof, and this opening is suitably plugged or sealed after the space 20 has been completely filled.

In practice, it is desirable that each water receiving and retaining cup 13 be filled to a substantially uniform level, and it is preferable that this level be determined with respect to the upper edge portions of the tray and mold members. As a convenient means to attain these ends, each division defining the individual cups 13 is provided with a passageway 22 which establishes communication between adjacent cups 15 so that the water within the mold member will seek a uniform level in each cup by flowing from one cup to another through the passageways, the depth of said passageways being such as to form visual markings indicative of the level to which the mold member as a whole, is to be filled. Moreover, the marginal edge of each cup 13 may be formed with sharply slanting surfaces 23 which terminate on a line substantially level with the bottom of the passageways 22 thus providing additional visual means for indicating the desired water level. The formation and location of the slanting surfaces 23 also facilitate removal of the ice cubes when raised in relation to the tray and mold members in the manner to be fully described hereinafter.

In order that the passageways 22 may readily be formed in the divisions defining the individual cups 13, the cross-pieces 15 and 16 of the wire frame 14 may be bent to provide substantially U-shaped portions accommodating such passageways.

In accordance with that form of the invention more clearly shown in Figures 2 and 6 each of the individual cups 13 has a substantially flat bottom 24 which is in direct contact with the bottom surface of the tray member 11. Preferably, the bottom 24 of each cup 13 is relatively thin thereby assuring increased conductivity, and accordingly hastening the freezing of the water within said cup.

In the form of the invention more clearly illustrated in Figures 7 and 8, the cups 13 are formed with a bottom 24a slightly spaced from the bottom surface of the tray member 11 and having a re-entrant portion 25, that is, a portion extending upwardly for a distance into the cups 13. This re-entrant portion may be of any suitable desired shape but as shown is preferably dome-shaped.

It is particularly to be noted that, in this latter form of the invention, the space between the bottom surface of the tray member 11 and the bottom 24a of the mold member 12, as well as the spaces between the adjacent surfaces of the cups 13 and between the surfaces of said cups and side walls of the tray member are filled with the relatively slow freezing solution, so that each cup is completely surrounded with said solution.

In using either type of ice cube molding tray, the cups 13 are filled with water to the level determined by the passageways 22 and terminating lower edge of the slanting surfaces 23. The tray is then placed on a shelf of the evaporator usually mounted within a household refrigerator where the water is frozen into ice cubes C during the normal operation of the refrigerator.

It is common knowledge that during freezing, the ice cubes become rigidly bonded with the

surfaces surrounding the same so that normally, the removal of the ice cubes is somewhat difficult. However, in accordance with the present invention, these difficulties are effectively overcome since the bond between the ice cubes C and their molding cups 13 is automatically broken and the ice cubes are lifted in relation to the tray during the freezing process of the solution which takes place subsequently to the freezing of the water within said cups into ice cubes.

In this connection, it will be appreciated that since the water within the cups 13 freezes first and because of the shape of the cups 13 and the particular association of the mold member 12 and tray member 11, the expansion resulting from the subsequent freezing of the solution about said cups acts against the latter with a positively directed and controlled lateral force as represented by the arrows A in Figures 6 and 9, thereby distorting the normal shape of said cups 13 and causing the ice cubes to break away from the latter and rise in relation thereto, whereupon the ice cubes may readily be picked out as and when needed.

In the form of the invention illustrated in Figures 7 and 9, a part of the expansion forces are also directed against the bottom 24a of each of cups 13, in a substantially vertical direction, as indicated by the arrows B in Figure 9, so that although the freezing of the water within said cups may be slower than with the form of the invention illustrated, for instance in Figure 2, there is the compensating effect resulting from the additional lifting action imposed upon the individual ice cubes.

In accordance with this invention, the control of the expansion forces for full and direct action on the individual ice cube molding cups to insure automatic loosening and lifting of said cubes is assured, due to the rigidity of the upper edge of the mold member and its fixed position with respect to the tray member. This control is further enhanced because the bottom of the tray member is such that it will resist "bowing" under action of the expansion forces developing during the freezing process, and, if found desirable or necessary, this resistance to "bowing" may be assured by providing the bottom of the tray member with rib-like formations extending lengthwise of said bottoms, for instance as shown at 26 in Figures 7 and 9.

It is to be understood that the invention is not limited to the use of any one specific solution for filling the space between the mold and tray members so long as the solution chosen has a freezing point lower than that of water and possesses at freezing an expansion percentage sufficient to cause the freezing and raising of the ice cube from its mold cup. For example, a mixture of water and salt consisting of approximately 23.6% salt by weight would fill the requirements of such a solution, since it freezes at a rate sufficiently slow to allow the water within the cups to freeze sufficiently solid before the solution freezes so that the ice cubes do not crumble under the expansion force liberated by the freezing solution, and since such a solution, at freezing, expands approximately 8% it is amply sufficient to free and raise the ice cubes from their molding cups.

It is also to be understood that the invention is not limited to the particular structures herein set forth as examples of possible embodiments, but that any modification which comes within

the scope of the subjoined claims is to be considered within the spirit of the invention.

I claim:

1. An ice making device comprising a tray member of relatively rigid material, an ice molding member of relatively pliable material mounted in said tray member, said ice molding member having side wall portions and a bottom portion, said bottom portion of the ice molding member having a reentrant area, said side wall portions and bottom portion with its reentrant area being disposed with respect to the adjoining surfaces of the tray member to provide a continuous space between said tray and molding member, and a solution in said space, said solution having a freezing point lower than that of water.

2. In an ice making device, a self-contained open top receptacle comprising outer and inner tray elements, said inner element being joined to the outer element so as to provide a sealed inter-space and having a pliable-walled pocket depending in said space, and a freezable medium adapted to expand upon freezing confined within said space and about said pocket, said freezable medium having a freezing point below that of water and substantially filling said space whereby expansion forces within said body resulting from freezing of the said medium may react through said pliable wall to displace a previously frozen ice mass upwardly in said pocket.

3. In an ice making device, a self-contained open top receptacle comprising outer and inner tray elements, said inner element being joined to the outer element so as to provide a sealed inter-space and having a pliable-walled pocket depending in said space, and a freezable medium adapted to expand upon freezing confined within said space and about said pocket, the walls of said pocket converging downwardly and said freezable medium having a freezing point below that of water and substantially filling said space whereby expansion forces within said body resulting from freezing of the said medium may react through said pliable wall to displace a previously frozen ice mass upwardly in said pocket.

4. In an ice making device, a self-contained open top receptacle comprising outer and inner

tray elements, said inner element being joined to the outer element so as to provide a sealed inter-space and having a plurality of pliable-walled pockets depending in said space, means for preventing displacement of the upper edge portions of said pockets from the normal plane of the top of said receptacle, and a freezable medium adapted to expand upon freezing confined within said space and about said pockets, said freezable medium having a freezing point below that of water and substantially filling said space whereby expansion forces within the body of freezable medium resulting from freezing of the latter may react through said pliable walls to displace previously frozen ice masses upwardly in said pockets.

5. In an ice making device, a self-contained open top receptacle comprising outer and inner tray elements, said inner element being joined to the outer element so as to provide a sealed inter-space and having a plurality of pliable-walled pockets depending in said space, means for preventing displacement of the upper edge portions of said pockets from the normal plane of the top of said receptacle, and a freezable medium adapted to expand upon freezing confined within said space and about said pockets, the walls of said pockets converging downwardly and said freezable medium having a freezing point below that of water and substantially filling said space whereby expansion forces within the body of freezable medium resulting from freezing of the latter may react through said pliable walls to displace previously frozen ice masses upwardly in said pockets.
